UNITED STATES PATENT OFFICE

HENRY P. BRAEUTIGAM AND WILLIAM C. HOLBROOK, OF DAYTON, OHIO, ASSIGNORS
TO FRIGIDAIRE CORPORATION, OF DAYTON, OHIO, A CORPORATION OF DELAWARE

REFRIGERATING APPARATUS

Application filed February 29, 1928. Serial No. 257,989.

This invention relates to refrigerating apparatus and more particularly to an insulated refrigerating cabinet adapted for mechanical refrigeration.

5 An object of this invention is to provide a refrigerating cabinet in which substantially all of the interior and exterior surfaces are made of porcelain covered sheet metal.

Another object of this invention is to provide 10 a refrigerator cabinet having outside walls made of porcelain covered sheet metal panels independently removable from the cabinet.

Another object of this invention is to provide 15 a refrigerator cabinet having exterior porcelain covered metal walls with means between panels of said walls for preventing chipping or breakage of the porcelain.

Another object of this invention is to provide 20 a frame made of wood for a refrigerator cabinet adapted to support porcelain covered sheet metal panels in a manner to prevent chipping and breaking of the porcelain.

Another object of this invention is to provide 25 a refrigerator with outer walls made of porcelain covered panels and in which a small number of fastening members for said panels are used and in which said members are hidden from view or are placed in inconspicuous parts of the cabinet.

Another object of this invention is to provide 30 a flexible spacer to be placed between porcelain covered sheet metal panels to prevent chipping of the porcelain.

Another object of this invention is to provide 35 a porcelain metal covered refrigerator cabinet with sound deadening means in the wall construction thereof.

Further objects and advantages of the 40 present invention will be apparent from the following description, reference being had to the accompanying drawings, wherein a preferred form of the present invention is clearly shown.

45 In the drawings:

Fig. 1 is a perspective view of a cabinet embodying features of our invention;

Fig. 2 is a vertical transverse cross-sectional view taken substantially along a middle plane of the cabinet;

Fig. 3 is a vertical cross-sectional view taken at right angles to Fig. 2 and substantially along the middle line thereof;

Fig. 4 is a horizontal cross-sectional view taken substantially at the center of the cabinet. 55

Fig. 5 is a horizontal cross-sectional view taken substantially along the middle line of the lower compartment of said cabinet;

Fig. 6 is a front elevation of a frame used 60 in the construction of said cabinet;

Fig. 7 is a side elevation of said frame;

Fig. 8 is a top elevation of said frame;

Fig. 9 is a bottom elevation of said frame;

Fig. 10 is an enlarged perspective view of 65 a corner of the frame shown in Figs. 6 to 9 inclusive, with the gussets omitted;

Fig. 11 is a perspective view of the corner shown in Fig. 10 with the members of the frame spread apart to show details of construction; 70

Fig. 12 is an enlarged detailed cross-sectional view taken substantially along the line 12—12 of Fig. 1;

Fig. 13 is a vertical section taken substantially along the line 13—13 of Fig. 12 with portions broken away to show the various members; and 75

Fig. 14 is an elevation of a flexible spacer shown in Fig. 12. 80

A cabinet in which features of our invention are embodied is generally designated as 20. In general, it comprises a frame 21 upon which is supported an outer casing generally designated as 22, an inner lining generally designated as 23, insulation generally designated as 24, and a cooling member generally designated as 25. 85

The frame 21 may be made of wood as hereinafter more fully described. Around the 90 frame may be placed the outer casing 22. The outer casing may be made of panels of porcelain coated sheet metal. The sides of the outer casing may be made of two panels 30 and 31 which extend from the bottom to the top of the cabinet and are provided with flanges on the two upright edges designated as 32 and 33 and a flange at the top indicated as 34. The front of the cabinet may be made of two panels 40, a central horizontal panel 100

41, an upper horizontal panel 42 and a center mullion panel 43. All of these front panels have flanges along their longitudinal edges which are adapted to embrace the frame members. Panels 41, 42 and 43 also have flanges at the ends. These panels can be attached to the frame by nailing through holes provided in the flanges along the longitudinal edges. The panels 30 and 31 are attached to the frame 21 by nailing the flanges 34 and by screws 35, with suitable washers, passing through holes at the bottom of said panels.

The back wall 45 may extend down to the lower compartment and may be held by the flanges 32 of the side panels 30 and 31. If the cabinet is not expected to be exposed at the back this rear wall need not be of enameled sheet metal. Screws 35a may pass through flanges 32 and back wall 45 into frame 21.

Wherever it is necessary for the flanges or edges of the inner or outer walls to cross members of the frame or to run along the same, grooves are provided to receive these flanges or edges. As shown in the drawings, grooves 50 and 51 are provided on the outside of the frame. Other grooves 78, 78a and 79 (Fig. 6) are also necessary in this particular embodiment. These grooves occur at the ends of the panel 41, at the ends of the panel 43, and also on the inner side of the frame at places corresponding to the ends of the panel 43 in order to allow the inner lining to cross the center mullion as hereinafter more fully described.

The inner lining 23 may be a box-like sheet metal member having its inner sides enameled. The edges of the opening of the lining 23 may be inwardly offset as at 46 to provide edges 47 parallel to the sides of the lining. An opening 52, slightly downwardly paneled, may be provided in the bottom of the lining in order to receive hermetically sealed therewith a defrosting drain 53, which passes through the lining and insulation into the lower compartment where it forms a liquid seal loop 48 and empties into pan 85.

In order to accommodate the panels as hereinbefore described the frame 21 may be constructed as follows: Two upright front corner struts 55 may have their ends cut as shown at 56 in order to receive the side top beams 57, also having ends cut as at 58 to fit in cut 56. The front top beam 59 may be made of two pieces, the rear portion 60 extending behind the front main portion of member 59 and being nailed thereto. If desired, of course, the main portion of member 59 and member 60 may be integral and the ends may be cut in a shape to receive the end of the strut 55 thus making beam 59 similar to beam 57. As shown in Figs. 10 and 11, a cut at the end of beam 59 forms the groove 51 hereinbefore described. The strut 65 has the groove 50 cut at its corner as does

the end of beam 57. In assembling these members, the strut 55 and beam 59 may be temporarily held together by means of corrugated nails 61 and a diagonally driven nail 62. The member 60 may then be nailed to the main front member of beam 59 and to the strut 55 by means of nails 63. The nailing of this member 60 secures the two members 55 and 59 together since the nails 63 extend at right angles to the grain of members 55, 60 and 59. An upright member 55a may be placed behind the strut 55 upon which the member 60 rests. This member 55a may be nailed across the grain onto member 55. The side beam 57 may then be screwed, by means of screws 64, onto the strut 55 after an additional nail 65 has been driven through strut 55 into beam 59. If desired, beam 57 need not be as thick vertically as beam 59 and hence will leave an opening 66 which is invisible after the panelling has been placed on the frame-work. As shown in Fig. 6, an offset 55b is provided in strut 55 in order that the door opening of the lower compartment 70 of the cabinet may be made larger so that refrigerating machinery may be inserted into the cabinet. The front panels 40 have offset 40b corresponding to offsets 55b. The flange along the inner longitudinal edge of each panel 40 may be continuous at the offset 40b.

The corners 71 and 72 of the cabinet are made as shown in Figs. 10 and 11 and the other corners of the cabinet may be made in any usual manner. Gussets 73, made of sheet metal and having holes punched therein, may be nailed at all corners of the cabinet. However, at the bottom, special gussets 74 may be substituted having inherent therein means for receiving the casters 75. These special gusset plates 74 may be of the type more fully described in the application of William C. Holbrook, Serial No. 258,006, filed February 29, 1928, executed concurrently herewith, for refrigerating apparatus.

Between the front struts 55 of the frame may be placed a horizontal beam 76 forming part of the bottom of the door jamb. Joining the beams 59 and 76, may be placed a center mullion strut 77. A beam 76b joins the struts 55 at the bottom. Grooves 78 and 78a, similar to grooves 51, may be placed between members 76, 76b and 55, and grooves 79 both in front and behind the strut 77 may be placed at the end of strut 77 where it joins beams 59 and 76 for receiving the flanges of the porcelainated panels as elsewhere described. The front struts 55 are connected to the rear struts 80 by means of beams 57 heretofore described, and also by middle beams 82 and bottom beams 83. The rear struts 80 may be joined by top beam 81, intermediate beam 82a and a bottom beam 83a. Horizontal brackets 84 may be secured to the members 76 and 82 to support the drip pan 85.

in a manner hereinafter more fully to be described. In order to fasten the beam 82a more securely, reinforcing wood members 80a may be nailed to struts 80 and may extend between beams 82a and 83a.

5 A method of making the grooves 79 in the rear of mullion strut 77 is by providing the strut 77 with a rear frame piece 77a shorter than the front part and nailed thereon. The 10 piece 77a is sufficiently shorter to provide grooves 79 in the rear of mullion strut 77. A rear porcelainized sheet metal rectangular panel 84a, having flanges on all four edges is placed over the piece 77a and nailed at the flanges to 15 said piece 77a. The end flanges of panel 84a are parallel and adjacent to the top and bottom edges 47 of the lining 23. If desired, flexible spacers, hereinafter described, may be placed between the edges 47 and the flanges 20 of panel 84.

In assembling the interior of the cabinet the lining 23 may be nailed at the edges 47 to the frame members 60, 55a and to a frame member 76a which may be nailed on the rear 25 of the horizontal door jamb member 76. Suitable holes are made in the lining 23 at the edges 47 before the enameling process, these holes being used for nailing the lining 23, as above described. Since the outside 30 panels are not assembled on the frame until after this operation, insulation 24 may be secured to the lining 23. A way of fastening the insulation is to coat the outer sides of the lining 23 with some asphaltic cement and to 35 coat the surfaces of slabs of insulating material, such as corkboard, and then to press the slabs against the outer sides of the lining 23. The asphaltic cement on the lining and on the slabs after cooling holds the slabs of 40 insulation securely in place. The bottom slab of insulation may be held in place additionally by a sheet metal member 85a which is secured to the frame members 82a and 82. The horizontal brackets 84 for the pan 85 45 may then be secured to member 76 and the member 82a.

After the insulation is in place, sound deadening sheets of flexible material, such as wall-board, may be secured to the frame to cover 50 the two sides. This material may also be placed over the top of the cabinet and narrow strips may be pasted on the front frame members over which the panel members 40, 41, 42 and 43 are to be placed. The wall-board heretofore described is designated generally as 86 in the drawings. If convenient, the top sheet of this material may be a single piece and the two sides may be covered with 55 two sheets each, one set extending for the length of the upper compartment and the other set extending for the length of the lower compartment 70. This material 86 has a sound deadening effect which removes the hollow sound generally present when cabinets 60 of this character are struck. In addition, this

material 86 forms a cushion which decreases the liability of breakage of the porcelain at the points where fastening means are used to attach the porcelainized panels to the frame.

After the wall-board 86 has been placed on 70 the cabinet the outer panels are secured to the frame-work. The panels 40 may be secured by screw 35 at the bottom and by nails at the flanges inside the door jamb.

The front panel 42 may then be placed over 75 the framework. The front panel 42 is secured by nailing the flanges within the door jamb. Before placing the panel 42, a flexible or compressible spacer generally designated as 87 may be secured to the panel 42. This flexible or compressible spacer may comprise a rubber strip 88 U-shape in cross-section adapted to hook over the flange of the panel member 42. After the members 40 and 42 80 may have been secured with the strip 88 in place a metal trim 89 may be placed over the rubber strip 88, this metal trim may be U-shaped in vertical cross-section and may have inwardly directed flanges 89a which fit around 85 the edge of the rubber strip 88. The arms 90 of the U-shaped member 89 then fit over the beam 59, and the arms 90 may be nailed to said beam 59. The top sheet of wall-board need not be placed on the cabinet until after 90 the trim 89 has been secured in place. The panel 41 may then be placed in position in a manner similar to the panel 42 with similar flexible spacers 87 at the ends. The center mullion panel 43 may then be placed on the 95 cabinet with flexible spacers 87 at its end similar to those placed at the end of panel 42. Door jamb molding, comprising strips 95, of wood or the like, may be secured by screws or 100 nails to trim the door jamb, and to cover the edges 47 and the flanges of the panels after the front is completed, the side panels 30 and 31 may be attached to the cabinet and a flexible spacer 91 may be placed between these panels 105 and the panels 40. This flexible spacer may be 110 similar to the spacer 88 heretofore described, but instead we may use the metal spacer 91 shown more fully in Figs. 12 and 14, if desired. This spacer may be T-shaped in cross-section, formed by bending a single long 115 strip of Monel metal into the form of a T, and with the bending being of a character which causes the edges of the strip to spread apart with a natural springiness to provide 120 flexibility to the spacer. One of the edges of the strip may have tongues 92 adapted to be wound around the vertical flange 24 of the member 40 to hold the spacer in place.

The side panels 30 and 31 may be wedged into the groove 50, between the spacer 91 and 125 the edges of the groove. These side panels may then be straightened against the sides of the cabinet, after which they may be secured by screws 35 at the bottom and by nails passing through the top flanges 34 into the 130

frame. The back wall member 45 may be placed on the cabinet before placing the side panels 30 and 31 and may be held temporarily in place by any suitable means until the side panels 30 and 31 are placed on the cabinet. Screws 35a may then be used to fasten members 30 or 31 and 45 by passing them through the flanges 32 and the back wall member 45 as heretofore described. The top member 93, comprising an inverted pan-shaped porcelainized sheet metal panel, may then be secured in place and screws 94 may be used near the corners of the top 93 to secure the top to the cabinet. These screws may also have suitable resilient washers interposed between the head of the screw and the porcelainized panel.

The cooling compartment 100 may be secured in place in the manner more fully described in the application of Francis E. Stevenson, Serial No. 257,999, filed February 29, 1928, executed concurrently herewith for refrigerating apparatus, to which reference is hereby made, if necessary, for further details. Briefly speaking, the cooling compartment is secured by fastening bolts through the lining 23 before the insulation is placed thereon, these bolts being of a type to allow the subsequent fastening of the cooling compartment walls to the lining 23. Within the cooling compartment, an evaporator 101 is placed and this may be of the flooded float controlled valve type adapted to receive liquid refrigerant and to return evaporated refrigerant to refrigerating machinery generally placed in the compartment 70 of the cabinet, or placed in the basement generally beneath the cabinet. The front wall of the cooling compartment is provided with an opening 104. The cooling unit 101 has backwardly beveled faces 104a forming an ice tray opening 105a. Through this opening, ice trays 105 may be inserted in, or removed from the cooling unit. The fronts of the ice trays 105 are adapted to close the opening 104.

A defrosting pan 106 may rest slidingly on shelves 107 secured to the walls of the cooling compartment or to the walls of the lining 23. An opening 108 may be provided in the side wall of the cooling compartment, and this opening, together with the various openings shown, provide for convection currents of air within the cabinet. The defrosting pan 106 may have its bottom sloping toward a drain arranged to discharge into the funnel 53a of drain 53.

Doors 110 of any suitable construction may be secured by means of fastening members comprising hinges 111 and locks 112. These fastening members 111 and 112 may have shims interposed between them and the metal work of the cabinet and the screws or bolts for these members may pass through the panels into the framework of the cabinet or of the door. This aids in holding the porce-

lained panels in place and removes strain from the panels by transferring the weight of the doors directly to the framework.

A lower door 113 may be placed in the opening of the compartment 70. This door may be hinged by merely providing cylindrical portions of rods adapted to rest on U-shaped brackets 114 so that the door 113, if desired, may be lifted from the box and a different door substituted therefor. A spring catch, not shown, may be provided within the cabinet at the top of door 113. When the refrigerating machinery is placed in the compartment 70, the door may be provided with louvers 115 which permit the passage of air through the compartment 70 to cool the condenser and compressor generally used. Usually rear wall 45 of the cabinet extends only to the frame member 82a thus providing an opening in the rear of compartment 70 for a more thorough circulation of air. However, when the refrigerating machinery is not to be placed in compartment 70, the rear of the compartment may be closed by any suitable cover and a front door may be substituted for door 113 which may be provided with trays or bins for storing food in the compartment. A suitable pan 116 is secured to the lower frame members for forming the bottom of the compartment 70, or for catching any oil that may drop from the refrigerating machinery.

The joint for the corner of the cabinet as shown in Figs. 10 and 11 may be slightly modified, for instance as shown in the application of William C. Holbrook, Serial No. 258,005, filed February 29, 1928, executed concurrently herewith, for refrigerating apparatus.

The type of washer which is interposed between the heads of screws 35 and the porcelainized panels may be, though not necessarily, somewhat as shown in the patent to Leon J. Barwood, 1,538,155, patented May 19, 1925. The screws 35 may be wood screws with heads of the countersinking variety having wedge-shaped bottoms. The washers also may have their inner edge wedge-shaped, so that the screws may be countersunk within the washers to present a neat appearance.

While the form of embodiment of the invention as herein disclosed, constitutes a preferred form, it is to be understood that other forms might be adopted, all coming within the scope of the claims which follow.

What is claimed is as follows:

1. An insulated refrigerator cabinet having a frame, a flat metal side panel secured to said frame and having flanges along its upright edges, one of said flanges being unexposed to the exterior of the cabinet, said side panel forming one corner only of said cabinet, and a metal front panel secured to said frame and having flanges along its upright edges.

edges, one of said last named flanges being unexposed to the exterior of the cabinet.

2. An insulated refrigerator cabinet having a frame, a flat metal side panel secured to said frame and having flanges along its upright edges, one of said flanges being unexposed to the exterior of the cabinet, said side panel forming one corner only of said cabinet, and a metal front panel secured to said frame and having flanges along its upright edges, one of said last named flanges being unexposed to the exterior of the cabinet, the unexposed flange of said side panel and of said front panel being adjacent each other.

3. An insulated refrigerator cabinet having a frame, a flat metal side panel secured to said frame and having flanges along its upright edges, one of said flanges being unexposed to the exterior of the cabinet, said side panel forming one corner only of said cabinet, and a metal front panel secured to said frame and having flanges along its upright edges, one of said last named flanges being unexposed to the exterior of the cabinet, the unexposed flanges of said side panel and of said front panel being adjacent each other, and a flexible spacer between said unexposed flanges and secured to one of said flanges.

4. An insulated refrigerator cabinet having a frame, a flat metal side panel secured to said frame and having flanges along its upright edges, one of said flanges being unexposed to the exterior of the cabinet, said side panel forming one corner only of said cabinet, and a metal front panel secured to said frame and having flanges along its upright edges, one of said last named flanges being unexposed to the exterior of the cabinet, the unexposed flanges of said side panel and of said front panel being adjacent each other, said front panel extending around a corner of said cabinet to form a portion of the side of said cabinet.

5. An insulated refrigerator cabinet provided with a front door opening and having a frame including upright corner struts; metal panels on each side of said cabinet having flanges along their upright edges; upright front metal panels on each side of said door opening each having flanges along their upright edges; a flange on each side panel being adjacent to and substantially parallel with a flange on a front panel.

6. An insulated refrigerator cabinet provided with a front door opening and having a frame including upright corner struts; metal panels on each side of said cabinet having flanges along their upright edges; upright front metal panels on each side of said door opening each having flanges along their upright edges; a flange on each side panel being adjacent to and substantially parallel with a flange on a front panel, each of said front panels being bent to form a corner of said cabinet.

7. An insulated refrigerator cabinet provided with a front door opening and having a frame including upright corner struts; metal panels on each side of said cabinet having flanges along their upright edges; upright front metal panels on each side of said door opening each having flanges along their upright edges; a flange on each side panel being adjacent to and substantially parallel with a flange on a front panel, and a flexible spacer between said adjacent flanges.

8. An insulated refrigerator cabinet provided with a front door opening and having a frame including upright corner struts; metal panels on each side of said cabinet having flanges along their upright edges; upright front metal panels on each side of said door opening each having flanges along their upright edges; a flange on each side panel being adjacent to and substantially parallel with a flange on a front panel, each of said front panels being bent to form a corner of said cabinet, and a flexible spacer between said adjacent flanges.

9. An insulated refrigerator cabinet having a frame and having its side and front outer walls made of porcelain coated metal panels secured to and independently removable from said frame, said panels having adjacent edges, and flexible spacers between said edges.

10. An insulated refrigerator cabinet having a frame and having its side and front outer walls made of porcelain coated metal panels, said panels having adjacent edges and inwardly directed flanges at said edges, and flexible spacers between said edges.

11. An insulated cabinet having a frame, comprising three members joined at a corner with outer surfaces establishing three planes at right angles to each other; said members having vertical grooves adjacent said corner; vertical metal panels covering some of said members having flanges at the edges adjacent each other inwardly directed in said grooves.

12. An insulated cabinet having a frame comprising three members joined at a corner with outer surfaces establishing three planes at right angles to each other; said members having vertical grooves adjacent said corner; vertical metal panels covering some of said members having flanges at the edges adjacent each other inwardly directed in said grooves; and flexible spacers between said flanges.

13. An insulated refrigerator cabinet having metal panels with adjacent and parallel edges forming a joint and a flexible spacer between said edges, said spacer being provided with a metal cover along the edge of the joint formed between said flanges.

14. An insulated refrigerator cabinet having metal panels with adjacent and parallel flanges and a U-shaped rubber spacer around

one of said flanges having a portion between said panels.

15. An insulated refrigerator cabinet having metal panels with adjacent and parallel flanges and a U-shaped rubber spacer around one of said flanges having a portion between said panels, and a metal cover for the portion of said spacer which is between said panel.

16. An insulated refrigerator cabinet having a frame, a flat metal side panel secured to said frame and having flanges along its upright edges, one of said flanges being unexposed to the exterior of the cabinet, said side panel forming one corner only of said cabinet, a metal front panel secured to said frame and having flanges along its upright edges, one of said last named flanges being unexposed to the exterior of the cabinet, the unexposed flanges of said side panel and of said front panel being adjacent each other, and a flexible spacer between said unexposed flanges.

17. A refrigerator cabinet having a frame, flat metal enamel covered panels secured to said frame and having adjacent and parallel edges, and a rubber spacer between said edges.

18. An insulated refrigerator cabinet having metal panels with adjacent and parallel flanges having inwardly directed edges, and a compressible spacer between said flanges, said spacer having a portion extending around one of the inwardly directed edges of one of said flanges.

19. An insulated refrigerator cabinet having sheet metal panels supported independent of each other, the panels having substantially straight parallel and adjacent inwardly projecting edge portions, and a compressible spacer compressed between said edge portions.

20. An insulated refrigerator cabinet having sheet metal panels supported independent of each other, the panels having substantially straight parallel and adjacent inwardly projecting edge portions, and a compressible rubber spacer compressed between said edge portions.

21. A cabinet comprising a frame structure provided with grooves, metal panels covering said frame structure, said panels having inwardly directed flanges at their adjacent edges and said flanges extending into said grooves, and flexible spacers between said adjacent edge flanges.

22. In testimony whereof we hereto affix our signatures.

HENRY P. BRAEUTIGAM.
WILLIAM C. HOLBROOK.
